UNITED STATES PATENT OFFICE.

EDWARD P. NOYES, OF WINCHESTER, MASSACHUSETTS, ASSIGNOR TO CHARLES F. BROWN, TRUSTEE, OF READING, MASSACHUSETTS.

VARIABLE-STANDARD BOILER-FEEDER.

No. 888,840.

Specification of Letters Patent.

Patented May 26, 1908.

Application filed October 2, 1906. Serial No. 337,144.

To all whom it may concern:

Be it known that I, EDWARD P. NOYES, a citizen of the United States, residing at Winchester, in the county of Middlesex and State 5 of Massachusetts, have invented certain new and useful Improvements in Variable-Standard Boiler-Feeders, of which the following is a specification.

This invention relates to automatic boiler feeders and it aims to remedy the consequences of an abnormally heavy steam draft on the boiler.

In certain services where the steam draft varies widely (as, for example, in supplying 10 a rolling-mill engine) the water in parts of the boiler may assume a false level which is not the actual mean water-level. This is especially noticeable in water-tube boilers where upon the occurrence of a heavy steam 15 draft the water-line will mount above the mean level in one drum and descend below it in another drum due to the reduced pressure and sudden release of steam bubbles from the water with a consequent upward 20 surging in the up-take tubes. If the gage-glass is on the drum which shows a depressed level, the boiler tender, if the feed is controlled by hand, will learn not to bring the feed up to the normal mean-level line at 25 times of heavy draft, but will keep the water only just in sight in the glass. But automatic feed regulators as now constructed and applied do not take cognizance of the false level and consequently either over-feed 30 or under-feed the boiler at times of heavy steam draft, according to whether the automatic regulator is controlled from a point of depressed false level or from a point of raised false level.

To overcome these objections my invention 35 comprises an automatic boiler-feeding apparatus having a shifting or variable standard of level and controlled by a mechanism sensitive to variations in the steam draft on 40 the boiler. If the regulator is attached to a point on the boiler showing raised false level when the steam draft is excessive its controlling mechanism operates to raise the standard level of the regulator 45 so that it will continue to feed boiler water up to a higher water-line in the drum or part of the boiler showing the abnormal rise. In other words it is then controlled by the crest 50 of the surge produced by excessive ebullition. If the regulator is attached to a drum

showing a depressed false level, the controller sensitive to steam draft will lower the standard level of operation of the regulator so that it is then controlled by the hollow of the surge, giving the boiler, however, in each 60 case, an actual mean water-level intermediate between the crest and hollow.

The particular form of automatic regulator employed is immaterial to my present invention. In the drawings I have shown four 65 different types of regulator of variable standard level.

Figure 1 represents a sectional view showing one form of my automatic apparatus applied to a boiler and adjusted to control the 70 water level from a boiler drum showing a depressed false level at times of heavy steam draft. Fig. 2 represents a view showing a different form of regulator with the invention applied thereto. Fig. 3 represents a 75 detail sectional view of a by-pass valve employed in the two foregoing forms. Fig. 4 represents a view showing a third form of the invention. Fig. 5 represents a fourth form.

The same reference characters indicate 80 the same parts in all the views.

Referring at first to Figs. 1 and 3, 10 indicates a steam and water drum which may be one of the upper drums of a water-tube boiler, from which leads a steam-pipe 11 containing 85 throttle-valve 12 and having steam inlet through a perforated dry pipe 13 within the boiler. 14 is a tubular casing within which the water-level of drum 10 is maintained by means of pipes 15, 16, said casing containing 90 concentric tubes 17, 18 having their lower orifices located respectively at a low level *a—a* and a high level *b—b*. The level *b—b* may represent the desired mean or normal water-line. The pipes 17, 18 connect at 95 their upper ends with chambers 19, 20, from which a constant slight leakage of steam takes place through release-valves 21, 22. 23 is a diaphragm connected with a throttle-valve 24 in the feed-line 25 and receiving on 100 its upper side the pressure of a water column in a pipe 26 connecting with the chamber 19 and in addition a variable steam pressure, while its lower side receives the pressure of a water column in a pipe 27, and in addition 105 the steady steam pressure of the boiler transmitted by way of casing 14 and pipe 15. Chamber 20 has a loop-pipe 28 connecting it with the summit of pipe 26 and containing 110 a valve-casing 29 in which is a valve 30 hav-

ing its stem attached to a diaphragm 31. On its lower side this diaphragm receives steam pressure from the interior of the boiler drum 10 through a pipe 32 connected with 5 casing 14, and on its upper side the pressure of a light spring 33 and steam pressure from the steam-pipe 11 by way of a connecting branch 34. The connection of this branch with the steam-pipe 11 is preferably between 10 the throttle 12 and the dry-pipe 13 as shown, and I further prefer to make the total area of the inlet holes of the dry-pipe such that a considerable drop in pressure of the outgoing steam will be caused at times of heavy draft 15 while at times of light draft the pressure drop will be inappreciable.

Considering the operation of the device, it will be seen that when the water-level in drum 10 is below line $a-a$, the steam pressures transmitted to opposite sides of diaphragm 23 are balanced and relative hydrostatic heads together with the weight of parts causes feed-valve 24 to open and permit the pump to raise the water-level. If 20 the water-line reaches the level $a-a$ so as to seal the pipe 17 at a time of normal steam draft, it will have no effect in unbalancing the diaphragm 23, for at such times the steam pressures on diaphragm 31 are balanced and spring 33 opens the valve 30 so as to admit boiler steam into chamber 19 by 25 way of pipes 18 and 28 and thus prevent any substantial reduction of the pressure in chamber 19 by way of the leakage-valve 21. The water then continues to feed until the 30 level rises to $b-b$ and since both pipes 17 and 18 are then sealed, the pressure in the variable-pressure chambers 19, 20 will be reduced by leakage through the valves 21, 22, 35 thus unbalancing the diaphragm 23 and causing the feed-valve 24 to diminish or stop the feed. If, however, the water-level in the 40 drum rises to the line $a-a$ at a time of abnormal steam draft it will find the by-pass 45 valve 30 in loop 28 closed because the resistance of the dry-pipe apertures 13 has produced a diminution of pressure in the steam-pipe 11 and above diaphragm 31, compared with the pressure existing in the 50 drum 10 and below said diaphragm. Accordingly the pressure in chamber 19 will be reduced by sealing of the pipe 17 and leakage through valve 22 and the diaphragm 23 will operate to control the feed-valve 24. The 55 boiler is thus controlled from the hollow of the surge in drum 10 which constitutes a depressed false level whereas the boiler has its actual mean water-line higher than the apparent line $a-a$, which is the result desired and is similar to the result attained when a 60 boiler tender keeps the water only just in sight on a gage-glass attached to a drum showing a depressed false level.

Fig. 2 shows a modified feed-regulator em-

ploying two diaphragms 35, 36 with variable-pressure chambers 37, 38 corresponding to the chambers 19, 20 of Fig. 1, and having concentric pendent dip-tubes 39, 40 both attached to feed-valve 24 and having inlets at the levels $a-a$ and $b-b$ respectively. A diaphragm 31 having connections similar to the ones shown in Fig. 1 controls a by-pass valve device 29 which is open when the steam draft through pipe 11 is normal, thereby disabling the upper diaphragm 35 whose controlling level is $a-a$, and is closed when the steam draft is heavy, whereby the diaphragm 35 assumes control at the lower false level $a-a$. The lower end of pipe 39 has a headed connection with the stem of the feed-valve whereby the diaphragm 36 may rise and close said valve without movement of the tube 39.

In both of the foregoing forms it will be seen that the regulator has two fixed standard levels of action, namely a normal or high level and a depressed level, the one or the other of which is operative according to whether the steam draft is normal or excessive.

Fig. 4 shows a feed-regulator of the general type illustrated in Fig. 1 but having only a single variable-pressure chamber and inlet pipe 17' whose lower inlet, however, may be automatically fixed at any point between maximum and minimum heights by the action of the diaphragm 31. In this case the tube 17' has a vertical slot 41 covering the desired range of water-line level and an external sleeve 42 with a helical slot 43. Rotation of this sleeve changes the height of the small aperture 44 common to said slots and the sleeve is rotated in one direction or the other by the application of outside power through oppositely-rotating clutch members 45, 46 with either of which a double clutch member 47 splined to the stem 51 of sleeve 42 is temporarily engaged by movement of the diaphragm 31. For the purpose of causing this mechanism to act in a "step by step" manner and automatically throw itself out of operation I prefer to provide the connections shown in the drawings according to which the diaphragm stem 52 is attached to a floating lever 53 fulcrumed on a rod 54 which is attached to one arm of a lever 55. The other arm of lever 55 engages a nut 56 mounted on the threaded lower end of stem 51. When the diaphragm 31 becomes unbalanced by the fall of pressure in steam-pipe 11, lever 53 will be oscillated to depress the double clutch-member 47 and engage it with the rotating clutch-member 46 whereby stem 51 and sleeve 42 are rotated to depress the inlet-aperture 44 of tube 17'. Such rotation of the stem 51 by reason of the pitch given to the screw-thread thereon at the same time causes nut 56 to be depressed and the

double clutch-member 47 to be raised to neutral position without any change of position in the diaphragm 31. As soon as steam-pressure-balance has been restored the diaphragm resumes its normal position, the double clutch-member 47 is raised into engagement with the upper rotating clutch-member 45 which rotates in the opposite direction from the lower clutch-member 46 and the 10 aperture 44 is raised until the upward travel of nut 56 has depressed the fulcrum of lever 53 sufficiently to restore the double clutch-member 47 to its neutral position. It will be understood that any equivalent mechanism may be employed for applying power to shift the standard level of the feed-regulator under control of the steam draft from the boiler. Fig. 5 shows a similar mechanism applied to rotate a threaded stem 48 and 20 shift the height of a float 49 which is connected to operate feed-valve 24 by a suitable mechanism, the float being held from rotation but permitted to rise and fall, and the stem 48 having connection 50 with the shaft 25 of the double clutch member whereby the two rotate together, but the float 49 is permitted to rise and fall under the influence of changing water-level in the drum 10.

Either of the forms of my invention shown 30 in Figs. 4 and 5 could be applied to control the boiler feed at times of abnormal steam-draft from a raised false level instead of a depressed false level by a suitable rearrangement of connections at the proper points 35 which will be obvious to any skilled mechanic. In like manner the forms shown in Figs. 1 and 2 may be rearranged to accomplish the same result by simple changes which do not vary the scope of my invention.

I claim:

1. The combination of a steam boiler having a steam outlet, automatic feed-regulating mechanism therefor controlled by the boiler water-level and having means for establishing said level at different heights, and 45 means sensitive to the rate of flow through said boiler outlet for varying said height.

2. The combination of a steam boiler having a steam outlet, automatic feed-regulating mechanism therefor having a shiftable 50 standard height of boiler-level control, a resistance in said outlet, and means controlled differentially by the steam pressure within the boiler and the pressure in said outlet on the remote side of the resistance, for varying 55 said standard level of the regulator.

3. The combination of a steam boiler having a steam outlet-pipe with a constricted aperture therein, a movable septum subject on opposite sides to the steam pressure within the boiler and the steam pressure in said outlet-pipe on the remote side of its constricted aperture, an automatic feed-regulator for the boiler having means subject to the boiler level at different heights for diminishing the boiler feed, and mechanism controlled by said septum and controlling said means for varying the height at which the feed-control is exercised.

In testimony whereof I have hereunto set 70 my hand in the presence of two subscribing witnesses, the twenty eighth day of September 1906.

EDWARD P. NOYES.
